Application filed March 17, 1919. Serial No. 283,275. Term of patent 14 years.

To all whom it may concern:

Be it known that I, DAVID E. VICTOR, a citizen of the United States, and a resident of the city of New York, borough of Manhattan, in the county and State of New York, have invented a new, original, and ornamental Design for a Badge, of which the following is a specification, reference being had to the accompanying drawing, forming a part thereof.

The figure represents a plan view of my design for a badge, which consists of a band or frame surrounding a conventionalized representation of a ship upon a wavy

ground, and the representation of a helmet and sword in the foreground, the band bearing the words "Association of" between periods, and the words "Army and Navy Stores, Inc."

The said design is printed, painted, molded, cast, carved, engraved, stamped, or otherwise marked, upon metal, wood, textiles, paper, glass, horn, bone or ivory.

I claim:

The ornamental design for a badge as shown and described.

DAVID E. VICTOR.
